SAFETY DEVICE FOR FIREARMS

Ralph Harold Baker, Independence, Mo.

Application March 30, 1944, Serial No. 528,736

7 Claims. (Cl. 42—70)

This invention relates to safety devices for firearms, and the primary object of the invention is to provide such a device which is quick-acting, efficient, and convenient to operate.

Another important object of the present invention is to provide a safety device of the above kind which is comparatively simple and durable in construction and capable of being readily applied to existing firearms with slight modification of the latter.

A further object of the invention is to provide a safety device of the above kind that includes an operating lever arranged and mounted so that it may be conveniently actuated by use of the thumb of the hand used to operate the trigger of the firearm and wherein forward pressure on the lever effects release of the safety device.

With the above and other objects in view, the present invention consists in the novel form, combination and arrangement of parts hereinafter more fully described, shown in the accompanying drawings and claimed.

In the drawings, wherein like reference characters indicate corresponding parts throughout the several views:

Figure 1 is a fragmentary side elevational view of a shotgun equipped with a safety device embodying the present invention, the shotgun being partly broken away and in section.

Figure 2 is a section taken on line 2—2 of Figure 1, the parts being in safety position as in Figure 1.

Figure 3 is a view similar to Figure 2, with the parts in released or firing position.

Figure 4 is an enlarged elevational view of the transverse assembly bolt of the firearm which is modified to receive parts of the present invention.

Figure 5 is an end elevational view looking toward the right of Figure 4.

Figure 6 is an inner elevational view of the operating lever.

Figure 7 is an enlarged side elevational view of the latching plunger of the safety device.

Figure 8 is an enlarged side elevational view of the locking bolt controlled by the latching plunger.

Referring in detail to the drawings, the present invention has been shown, merely by way of example, as applied to a shotgun having a breech housing 5 carrying a stock 6 and provided at the bottom with a trigger plate 7 on the under side of which is formed a guard 8 for the trigger 9. Extending transversely of the lower portion of the breech housing 5 rearwardly of the trigger guard 8 is an assembly bolt 10 having an end

threaded, as at 11, to screw into one side of the breech housing 5 and provided at the other end with a circular head 12 received in a recess 13 provided in the opposite side of the breech housing 5.

In accordance with the present invention, the bolt 10 has an axial bore forming an elongated socket 14, and slidably in this socket is a latch bolt including a relatively large portion 15, a reduced portion 16 and a head 17 on the inner end of the reduced portion 16, the free end of the large portion 15 being tapered or pointed, as at 18. This latch bolt is yieldingly projected beyond the open end of the socket 14 by means of a helical compression spring 19 disposed in the inner end portion of socket 14 and interposed between the inner wall of the latter and the head 17 of the latch bolt. A passage 20 is provided through the trigger plate 7 rearwardly of the trigger 9 and extends rearwardly and upwardly in line with an opening 21 provided in the bolt 10. Slidable in the passage 20 and opening 21 is a locking bolt 22 in the form of a straight rod, as shown clearly in Figure 8.

The invention further includes a lever 23 having a pivot opening 24 receiving a bushing provided with a head 25 countersunk in a recess of the breech housing 5, as shown in Figure 2. This recess communicates with recess 13, and the head 25 of the bushing engages in an arcuate recess 26 provided in the head 12 of bolt 10 so that the latter is restrained against turning and thereby becoming loose. A screw 27 passes through lever 23 and its bushing and is threaded into the side of breech housing 5, as at 28. In this way, the bushing provided with head 25 is secured in place and the lever 23 is retained on this bushing for forward and rearward rocking movement about a horizontal axis transverse to the breech. The lever 23 is formed in its inner side or face with a recess 29, and engaging in this recess is the projecting end of a lateral pin 30 having one end fixed in a socket formed in the adjacent side of the breech housing 5. The recess 29 is simply made of circular form for convenience in forming it, the purpose being to provide a recess, opposed portions of the wall of which coact with the projecting end of stop pin 30 to limit the swinging movement of lever 23 from the dotted line to the full line position of Figure 1, and vice versa. Also formed in the inner side or face of lever 23 are two concave recesses 31 and 32 located below the pivot opening 24 and selectively registerable with the tapered end 18 of the latch bolt. The recess 31 is relatively small and shallow, while

the recess 32 is relatively larger and deep. Also, recess 31 is arranged to receive the end of the latch bolt when the lever 23 is swung to the rearward full line position of Figure 1, while recess 32 is arranged to receive the tapered end of the latch bolt when lever 23 is swung forwardly to the dotted line position of Figure 1.

The arrangement is such that when lever 23 is swung to the full line position of Figure 1, the latch bolt engages recess 31 so that the latch bolt is held by lever 23 in an inwardly slid position with the adjacent end of locking bolt 22 impinging the larger portion 15 of the latch bolt. In that position, the locking bolt 22 is slid forwardly to the position of Figure 1 so as to engage trigger 9 at the back of the latter and prevent rearward pulling of the trigger for firing the firearm. On the other hand, when the lever 23 is swung to the dotted line position of Figure 1, the latch bolt is allowed to enter the larger recess 32 so that the latch bolt is slid outwardly by spring 19 until the reduced portion 16 of the latch bolt coincides with the rear end of locking bolt 22. When this is done, rearward sliding movement of the locking bolt 22 is permitted so that the trigger 9 may be pulled rearwardly to fire the firearm. It is to be noted that, although the lever 23 is arranged on the left side of the breech housing in the construction shown, for use by persons who use the right hand to actuate the trigger, it may be readily mounted on the right side of the breech housing for use by those who use their left hand to actuate the trigger. It is only necessary to note that this change simply involves arrangement of the screw 27 and pin 30 on the right side of the breech housing and provision of the socket 14 by counterboring the bolt 10 inwardly from its threaded end instead of inwardly from its headed end. In either case, the lever 23 is provided at its upper end with a thumb knob or thumb piece 33, adapted to be pressed for swinging the lever. It is particularly noted that the lever 23 is so located that it may be conveniently actuated by the thumb of the hand employed to actuate the trigger 9, by simply straightening the thumb and using it to press upon the knob or thumb piece 33. Due to the relatively close relation of recesses 31 and 32, the device is quick-acting, convenient to use, and easy to operate. Also, it will be seen that the device is compact, simple and durable, and may be readily applied to existing firearms with a minimum modification of the same. The concave form of recesses 31 and 32 and the rounded tapered form of the end 18 of the latch bolt provide a camming action that permits intentional shifting of lever 23 in either direction. At the same time, the lever 23 is effectively held against accidental pivotal movement unless forcibly or manually actuated. An advantage of the invention is that the lever 23 is actuated by the thumb and not the trigger finger. Also, in order to release the safety device and condition the firearm for firing, forward pressure is applied to the upper end of lever 23 in a natural manner by the thumb of the hand employed to actuate the trigger.

From the foregoing description, it is believed that the construction and operation, as well as the advantages of the present invention, will be readily understood and appreciated by those skilled in the art. Minor changes in the details of construction illustrated and described are contemplated, such as fall within the spirit and scope of the invention as claimed.

What I claim is:

1. In a firearm having a trigger and a breech housing provided with a trigger plate, a transverse assembly bolt extending across the breech housing rearwardly of and above the trigger, said assembly bolt having an axial socket open at one end of the bolt and at one side of the breech housing, a latch bolt slidable in said socket and having a tapered outer end, said latch bolt further having a relatively large portion and a smaller reduced portion, a spring normally acting to project said latch bolt, a trigger locking bolt slidable through the trigger plate and having one end arranged behind the trigger and the other end registered with the latch bolt, and a lever pivoted on a side of the breech housing and operable to retract the latch bolt in position to present the larger portion of the latter to the adjacent end of the locking bolt for holding said locking bolt in forwardly moved position engaged behind the trigger to prevent pulling of the latter, said lever being further operable to release said latch bolt and permit projection of the latter by said spring so as to register the reduced portion of said latch bolt with the adjacent end of the locking bolt and to thereby permit rearward movement of the locking bolt and pulling of the trigger.
2. In a firearm having a trigger and a breech housing provided with a trigger plate, a transverse assembly bolt extending across the breech housing rearwardly of and above the trigger, said assembly bolt having an axial socket open at one end of the bolt and at one side of the breech housing, a latch bolt slidable in said socket and having a tapered outer end, said latch bolt further having a relatively large portion and a smaller reduced portion, a spring normally acting to project said latch bolt, a trigger locking bolt slidable through the trigger plate and having one end arranged behind the trigger and the other end registered with the latch bolt, and a lever pivoted on a side of the breech housing and operable to retract the latch bolt in position to present the larger portion of the latter to the adjacent end of the locking bolt for holding said locking bolt in forwardly moved position engaged behind the trigger to prevent pulling of the latter, said lever being further operable to release said latch bolt and permit projection of the latter by said spring so as to register the reduced portion of said latch bolt with the adjacent end of the locking bolt and to thereby permit rearward movement of the locking bolt and pulling of the trigger.
3. In a firearm having a trigger and a breech housing provided with a trigger plate, a transverse assembly bolt extending across the breech housing rearwardly of and above the trigger, said assembly bolt having an axial socket open at one end of the bolt and at one side of the breech housing, a latch bolt slidable in said socket and having a tapered outer end, said latch bolt further having a relatively large portion and a smaller reduced portion, a spring normally acting to project said latch bolt, a trigger locking bolt slidable through the trigger plate and having one end arranged behind the trigger and the other end registered with the latch bolt, and a lever pivoted on a side of the breech housing and operable to retract the latch bolt in position to pre-

sent the larger portion of the latter to the adjacent end of the locking bolt for holding said locking bolt in forwardly moved position engaged behind the trigger to prevent pulling of the latter, said lever being further operable to release said latch bolt and permit projection of the latter by said spring so as to register the reduced portion of said latch bolt with the adjacent end of the locking bolt and to thereby permit rearward movement of the locking bolt and pulling of the trigger, said lever having relatively small shallow and relatively large deep recesses in the inner face thereof for selective reception of the tapered end of the latch bolt and constituting the means for causing retraction or permitting projection of said latch bolt, said lever having a recess in its inner side, and a stop pin carried by the breech housing and projecting into said recess to limit swinging movement of the lever.

4. In a firearm having a trigger and a breech housing provided with a trigger plate, a transverse assembly bolt extending across the breech housing rearwardly of and above the trigger, said assembly bolt having an axial socket open at one end of the bolt and at one side of the breech housing, a latch bolt slidable in said socket and having a tapered outer end, said latch bolt further having a relatively large portion and a smaller reduced portion, a spring normally acting to project said latch bolt, a trigger locking bolt slidable through the trigger plate and having one end arranged behind the trigger and the other end registered with the latch bolt, and a lever pivoted on a side of the breech housing and operable to retract the latch bolt in position to present the larger portion of the latter to the adjacent end of the locking bolt for holding said locking bolt in forwardly moved position engaged behind the trigger to prevent pulling of the latter, said lever being further operable to release said latch bolt and permit projection of the latter by said spring so as to register the reduced portion of said latch bolt with the adjacent end of the locking bolt and to thereby permit rearward movement of the locking bolt and pulling of the trigger, said lever having relatively small shallow and relatively large deep recesses in the inner face thereof for selective reception of the tapered end of the latch bolt and constituting the means for causing retraction or permitting projection of said latch bolt, said recesses being arranged so that retraction of the latch bolt is effected upon rearward movement of the upper end of the lever and projection of the latch bolt is permitted upon forward movement of the upper end of said lever.

5. In a firearm having a trigger and a breech housing provided with a trigger plate, a transverse assembly bolt extending across the breech housing rearwardly of and above the trigger, said assembly bolt having an axial socket open at one end of the bolt and at one side of the breech housing, a latch bolt slidable in said socket and having a tapered outer end, said latch bolt further having a relatively large portion and a smaller reduced portion, a spring normally acting to project said latch bolt, a trigger locking bolt slidable through the trigger plate and having one end arranged behind the trigger and the other end registered with the latch bolt, and a lever pivoted on a side of the breech housing and oper-

able to retract the latch bolt in position to present the larger portion of the latter to the adjacent end of the locking bolt for holding said locking bolt in forwardly moved position engaged behind the trigger to prevent pulling of the latter, said lever being further operable to release said latch bolt and permit projection of the latter by said spring so as to register the reduced portion of said latch bolt with the adjacent end of the locking bolt and to thereby permit rearward movement of the locking bolt and pulling of the trigger, and a thumb piece on the upper end of said lever within convenient reach of the thumb of the hand positioned to operate the trigger.

6. In a firearm having a trigger and a breech housing provided with a trigger plate, a transverse assembly bolt extending across the breech housing rearwardly of and above the trigger, said assembly bolt having an axial socket open at one end of the bolt and at one side of the breech housing, a latch bolt slidable in said socket and having a tapered outer end, said latch bolt further having a relatively large portion and a smaller reduced portion, a spring normally acting to project said latch bolt, a trigger locking bolt slidable through the trigger plate and having one end arranged behind the trigger and the other end registered with the latch bolt, and a lever pivoted on a side of the breech housing and operable to retract the latch bolt in position to present the larger portion of the latter to the adjacent end of the locking bolt for holding said locking bolt in forwardly moved position engaged behind the trigger to prevent pulling of the latter, said lever being further operable to release said latch bolt and permit projection of the latter by said spring so as to register the reduced portion of said latch bolt with the adjacent end of the locking bolt and to thereby permit rearward movement of the locking bolt and pulling of the trigger, said assembly bolt having a head provided with a peripheral recess, and a pivot bushing for the lever having a head engaged in the recess in the head of the assembly bolt to prevent turning and loosening of the latter.

7. In a firearm having a breech housing provided with a trigger plate, and a trigger beneath the breech housing, a transversely sliding spring-projected latching bolt, a lever pivoted on one side of the breech housing upon an axis transverse to the latter and engageable by said latching bolt to releasably retain said lever in either a forwardly or rearwardly swung position, a locking bolt slidable through the trigger plate and having one end disposed behind the trigger and the other end registered with the latching bolt, said latching bolt having a large portion and a reduced portion respectively aligned with the locking bolt when the latching bolt is retracted and when it is projected, so as to respectively prevent rearward movement of the locking bolt and pulling of the trigger and to permit such rearward movement of the locking bolt and pulling of the trigger, said lever having means to release and permit the projection and to cause the retraction of the latching bolt in the respective positions of the lever.

RALPH HAROLD BAKER.
